UNITED STATES PATENT OFFICE.

ALPHONSE OUDRY, OF PARIS, FRANCE.

IMPROVEMENT IN BRIDGES.

Specification forming part of Letters Patent No. 35,251, dated May 13, 1862.

To all whom it may concern:

Be it known that I, ALPHONSE OUDRY, of Paris, in the Empire of France, engineer of the Imperial Corps of "Ponts and Chaussées," have invented new and useful Improvements in the Construction of Suspension-Bridges; and I do hereby declare the nature of my said invention and in what manner the same is to be performed to be particularly described and ascertained in and by the following statement thereof, reference being had to the drawings hereunto annexed—that is to say:

My invention consists in constructing suspension-bridges in such manner that when one portion of the platform or roadway is subjected to a greater burden than other portions it does not become distorted or put out of shape, neither is the structure itself liable to oscillate. The platforms of suspension-bridges as usually made are connected to one or several flexible or jointed cables or chains, the whole being equally balanced under the weight of the structure, and being flexible are capable of being put out of shape. The action of an overload applied to one particular part of the platform alters the equilibrium and produces a distortion, and consequently a fresh equilibrium has to be found. The distortion is increased in proportion as the overload is applied to the platform of the bridge in a confined space. It is, however, decreased in proportion as the overload is applied to a larger portion of the length of the platform, so that if this overloading is spread over the whole length of the platform the primitive equilibrium will be practically maintained. So a suspension-bridge, although made with flexible chains, would become a rigid bridge provided the platform was sufficiently rigid to overcome any effect of partial or undue overloading.

My invention further consists in preventing the suspension-chains from losing their original curve. Although still flexible, they will not be deranged by an excessive or partial loading of the platform. I obtain this result by forming a means of suspension with two parabolic chains or cables, A B C D E and A' B' C' D' E, as shown in Fig. 1 of the accompanying drawings, both in the same plane of suspension, meeting in the middle, as at C, and uniting into one at the pillars A and E, leaving between them the spaces A B C B' and C' D' E D large enough to comprise all variations of the curves that each single chain

would take if unduly loaded on one particular part of the platform. These spaces are filled up by connecting-rods, which maintain the chains in their relative positions. When, therefore, the bridge is loaded upon a given point of the platform, the effort of the tension will be to become closer to the lower chain, which is immediately over the loaded part, and to become closer to the upper chain in the corresponding point in the other half. By the introduction of other diagonal rods, in conjunction with the hereinbefore-mentioned connecting-rods, the surplus strain on either cable or chain will be communicated to the other, by which means the strain will be equalized.

The plane of suspension which contains the suspension-rods which connect the platform with the chains may be placed vertically, and to prevent lateral motion to the platform they may be placed at an angle with the plane of the platform. I make use of inclined suspension-rods on the plane of the platform, which will lead to the employment of rollers or sectors placed on planes perpendicular to the plane of suspension, S, Fig. 2, being the cross-section, and A B in Fig. 2 being the plan perpendicular to the plane of suspension. To prevent the swinging or oscillation of the platform and the twisting or shaking of the suspension-rods, the platform must be as rigid as possible. To obtain this rigidity, I prefer to employ a platform constructed on the system shown in drawings, Fig. 2, A, in which the rigidity of the lattice will allow the suspension-rods to be farther apart, so that it will not be necessary to employ more than one suspension-rod to every two or three cross-tie pieces, as shown in Fig. 5.

When the span or opening of the bridge is of extraordinary width, I find it convenient to use suspension-rods all contained in the same plane of suspension, but some projecting vertically and others placed obliquely, connecting them together, forming a kind of lattice or rigid whole, (*ensemble*.) If the suspension-rods all project vertically, I find it convenient to place diagonal tie-pieces up to a certain height, which add greatly to the rigidity. If four double chains are connected together by straight rigid bars or rods, maintaining the chains in their respective planes of suspension, as seen at Fig. 10, the action of the wind coming in the direction of the arrow F' cannot put the chains out of their po-

sition of equilibrium as long as the momentum of F' with regard to $a' b' c' d'$ is inferior to the sum of the momentum of weight of each of the groups of the system of suspension, the first with regard to a' , the second with regard to C' .

When the platform requires to be attached close to the chains, the cross-tie pieces above mentioned cannot be employed in the middle of the span, as they would interfere with the traffic. In this case the two double chains on the side of the platform should be connected together, leaving the middle space free. Then each of the tie-pieces, in a lattice or other form, is firmly connected with the rigid platform. This is not shown in the drawings, but is a necessity of position.

In giving a convenient inclination to the planes of suspension, and in rendering them rigid by inserting cross-tie pieces, I may always destroy the tendency to distortion induced by a horizontal force acting laterally on the four double chains, the line $a b c d$ in Fig. 10 being fixed in space, and the platform being sustained on one side by the oblique rods $a m$ and $b m$, and on the other side by the oblique rods $c n$ and $d n$. The action of the wind in the direction of the arrow G' upon the platform cannot force the platform on one side as long as the momentum of G' with regard to $a b c d$ is inferior to the momentum of weight of the platform suspended in m with regard to a , and suspended in n with regard to c . By conveniently inclining the suspension-rods—that is to say, the plane of suspension—and ballasting the platform properly I can always render the platform immovable under the action of the wind.

In the first part of this specification I have shown the means by which I can, with the aid of cables or chains, construct a suspension-bridge which cannot be put out of form. I have said that to arrive at this result it was necessary that the two cables, $A B C D E$ and $A B' C D' E$, (see Fig. 14, which shows the position of the chains with the rods in zigzag, A and E being the points of suspension,) being disposed in a manner to comprise all the curves of distortion or deformity which a flexible cable can take, I maintain them in their position by vertical rods. I have also before observed that to transport to the portion of the cable on which there is the least tension the excess of tension which exists on the other it is necessary to place oblique and diagonal rods running from the foot of one upright to the next, and reciprocally. In this case the diagonal rods have only to resist the tension, and all tendency to compression is destroyed by the uprights. These may be replaced by the zigzags, as shown in Fig. 14, which, as required, will resist sometimes tension, sometimes compression. The zigzags may be strengthened or stiffened by the tie-pieces g , Figs. 11 and 12. I prefer the use of steel or alloys of steel cast,

tempered, hardened, or otherwise, in erecting these suspension-bridges, and cables of steel wire either tempered or hardened, or otherwise, may be used.

Fig. 1 is a diagram of the parabolic cables. Fig. 2 shows the new system of suspension in longitudinal elevation and in section. Figs. 3 and 4 show the assemblage or junction of the lower links of a chain cable with the suspension-rods and the different tie-pieces for a bridge of moderate span, Fig. 3 being the side view, and Fig. 4 being the plan, of such assemblage. Fig. 5 is a portion of the longitudinal elevation of a bridge of wide span, showing the diagonal tie-pieces. Figs. 6 and 7 show the same assemblage as Figs. 3 and 4, but for a bridge of extraordinary span, in which the links are made of circular section; Figs. 8 and 9, the same assemblage, but the bars are flat. Fig. 10 is a transverse section of a bridge in which four double chains of suspension are employed, and also shows the position and disposition of the suspension-rods placed obliquely to the plane of the platform, two inclining outward and two inward, with cross-ties in lattice connecting together the four double chains. Fig. 11 shows the assemblage of the chains with the connecting-rods in zigzag. Fig. 12 is the section of Fig. 11 at the line 1 2. Fig. 13 is the view of the zigzag rods seen from above. These zigzag rods may be replaced by vertical and diagonal rods used between two chains, as shown in Fig. 2. Fig. 14 is the chain with zigzag tie-pieces. Fig. 15 shows the section of a tie-piece which might be conveniently used in the zigzags.

Having now described the nature of my said invention and in what manner the same is to be performed, I declare that I claim as my improvements in the construction of suspension-bridges—

1. The employment of double parabolic cables or chains, as hereinbefore described, and shown in the accompanying drawings.
2. The employment of two series of rods set obliquely to the plane of the platform, substantially as hereinbefore described, and shown at Fig. 10 of the accompanying drawings.
3. The employment of rigid tie-pieces to overcome the effect of a horizontal force acting laterally upon the four double chains or systems of suspension which would otherwise tend to deform, distort, or alter their form, together with the means described to replace such tie-pieces in the middle of a bridge or viaduct, so as not to impede the circulation, all as hereinbefore described and illustrated with reference to the accompanying drawings.

In testimony whereof I have signed my name to this specification before two subscribing witnesses.
